UNITED STATES PATENT OFFICE.

WILLIAM S. AUSTIN, OF KANSAS CITY, MISSOURI, ASSIGNOR OF ONE-HALF TO
NELLINE F. AUSTIN, OF KANSAS CITY, MISSOURI.

ATTACHMENT FOR TYPOGRAPHICAL MACHINES.

Application filed March 22, 1927. Serial No. 177,337.

My invention relates to attachments for linotype and kindred machines, and the present invention pertains more particularly to mechanism for adjusting the movable vise jaw which regulates the length of the lines of the subject matter composed on said machines.

The object of my invention is to provide an attachment of the character above stated whereby the movable vise jaw can be quickly and accurately adjusted, and in order that the invention may be fully understood reference will now be made to the accompanying drawings, in which:

15 Fig. 1 is a plan view of a linotype vise equipped with my attachment.

Fig. 2 is an end elevation of the parts disclosed by Fig. 1.

Fig. 3 is an irregular cross section on line 20 3-3 of Fig. 1.

Fig. 4 is a detail perspective view of important features of my attachment.

Fig. 5 is an irregular cross section on line 25 5 of Fig. 1.

Fig. 6 is a detail perspective view of a frame constituting a portion of my attachment.

Fig. 7 is a detail perspective view of a lever forming part of the attachment.

30 Fig. 8 is a detail sectional view of a bolt for locking the attachment in any of its adjusted positions.

Referring in detail to the different parts, 2 designates the vise bed which is provided 35 at its rear portion with a fixed jaw 4 and a movable jaw 6. 10 designates a scale secured to the upper right hand portion of the vise bed 2 and calibrated in the usual manner. 12 designates a bracket secured to the left 40 end of the vise bed 2. 52 designates an abutment rod which is slidably mounted in a guide 46 secured to the rear side of the vise bed. Said abutment 52 has peripheral 45 grooves 54 for engagement by a bolt 44, whereby said abutment 52 is secured at any point of its adjustment. All of the foregoing parts may be of ordinary or any preferred construction.

Referring more particularly to the parts 50 constituting my attachment, 14 designates a frame which is firmly secured to the left end of the vise bed 2 and disposed on top of the bracket 12.

55 16 designates what I term an index bar which is slidably mounted in a slot 18 ex-

tending longitudinally of the upper portion of the vise bed 2. Said index bar 16 is arranged beside the scale 10 and has suitable means such as an index mark 20 for cooperating with the scale 10 in obtaining proper 60 adjustment of the movable jaw 6 from the fixed jaw 4. The left portion of the index bar 16 extends through a slot 22 in the frame 14 and is provided with rack teeth 24 for engagement with a pinion 26 fixedly 65 mounted upon a shaft 28 provided at one end with a knob 30.

The shaft 28 is rotatably and slidably mounted in the upper portion of the frame 14 and its end opposite the one carrying the 70 knob 30 is notched as indicated at 32 for engagement with the bifurcated upturned end 34 of a lever 36 mounted upon a pivot 38 extending through a vertically-grooved portion 40 of the frame 14. 75

The end of the lever 36 opposite the bifurcated end 34 projects into the notched portion 42 of the vertically-disposed bolt 44 which is slidably mounted in the bracket 46. The free end of the lever 36 is normally 80 pressed down by a spring 48 secured to the top of the vise bed 2 and extends across the index bar 16 to coat with the pinion 26 in holding said index bar in the slot 18.

The lower end of the bolt 44 has a longitudinal slot 50, through which the abutment 52 extends. The slot 50 has teeth 56 for entering the grooves 54 and thereby positively securing the abutment 52 at any point of its adjustment. The abutment 52 is firmly secured at its left end to the corresponding end of the index bar 16 through the intermediary of an arm 57, while the right end of said abutment 52 is adapted to contact the movable vice jaw 6 and adjust it towards the 95 fixed vice jaw 4.

Briefly stated the operation is as follows: When the index bar 16 is to be adjusted longitudinally in either direction to bring the index mark 20 into registry with the desired 100 graduation upon the scale 10, the knob 30 is drawn backwardly to cause the lever 36 to raise the bolt 44 out of engagement with the abutment 52 to release the latter. While still pulling backwardly upon the knob 30 105 the same is rotated to the right or left to cause the pinion 26 to shift the index bar 16 to the desired point. As the index bar 16 is shifted as stated, it, through the intermediary of the arm 57, shifts the abutment 110

52 the desired distance from the fixed jaw 4, at which point it is locked by releasing the knob 30 so that the spring 48 will depress the bolt 44 into positive engagement with the grooved portion of said abutment 52, which latter thereupon constitutes a stop for limiting the movement of the vise jaw 6 away from the vise jaw 4 and thereby controlling the length of the lines of the composition.

By constructing and arranging my attachment in the manner above pointed out it may be installed upon the vise bed 2 without making changes in the latter, and hence my attachment can be readily substituted for the one now in general use.

While I have shown and described the preferred construction of my device, I reserve the right to all such changes and modifications as properly fall within the spirit and scope of the invention as claimed.

Having thus described my invention, what I claim and desire to secure by Letters Patent, is:

25 1. In combination with a vise of the character described provided with a scale and an abutment for limiting the movement of the movable vise jaw from the fixed vise jaw, an index bar movably mounted upon said vise for coacting with the scale in adjusting said abutment into proper relation with the fixed vise jaw, means for securing said abutment at any point of its adjustment, and rotary means engaging the index bar for moving the latter and the abutment.

30 2. In combination with a vise of the character described provided with an abutment for limiting the movement of the movable vise jaw from the fixed vise jaw, a bar slidably mounted upon said vise and connected

to the abutment for adjusting the latter into proper relation with the fixed vise jaw, said bar having rack teeth thereon, and a pinion intermeshing with said rack teeth for adjusting the bar.

3. In combination with a vise of the character described provided with an abutment for limiting the movement of the movable vise jaw from the fixed vise jaw, a bar movable longitudinally upon the vise for adjusting said abutment into proper relation with the fixed vise jaw, means for locking the abutment at any point to which it is adjusted by said bar, rack and pinion means for adjusting said bar, a lever for disengaging the locking means from said abutment, and manually controlled means capable of rotation for actuating said rack and pinion means and capable of longitudinal movement for actuating said lever.

4. In combination with a vise of the character described provided with a scale and an abutment for limiting the movement of the movable vise jaw from the fixed vise jaw, a frame fixedly mounted upon the vise, an index bar slidably mounted upon the vise and in said frame for coacting with the scale in adjusting said abutment into proper relation with the fixed vise jaw, a pinion for sliding said index bar, a shaft rotatably and slidably mounted in the frame and upon which said pinion is fixedly mounted, means for locking the abutment at any point to which it is adjusted by said index bar, and a lever mounted in the frame and actuated by said shaft for disengaging said locking means from the abutment.

In testimony whereof I affix my signature.

WILLIAM S. AUSTIN.
